UNITED STATES PATENT OFFICE.

LESLIE M. PAGE, OF MAPLEWOOD, NEW JERSEY, AND LOUIS MEYLACH, OF BROOKLYN,
NEW YORK.

TWO-STATION PRINTING PRESS.

Application filed March 24, 1923. Serial No. 627,273.

To all whom it may concern:
Be it known that we, LESLIE M. PAGE and LOUIS MEYLACH, citizens of the United States, and residing, respectively, at Maplewood, in the county of Essex and State of New Jersey, and at New York, borough of Brooklyn, in the county of Kings and State of New York, have invented certain new and useful Improvements in Two-Station Printing Presses, of which the following is a specification.

This invention relates to two-station printing presses and has for its object to provide a printing press of the class specified, simple in construction and efficient in operation.

The general character of printing press to which our improvements are applied is illustrated as of the bed and platen type, wherein the form carrier is oscillated through a slight angle in approximately vertical position, toward and away from which the platen is oscillated. The Chandler and Price press is a familiar type of this style of press. It will be understood that our improvements are not limited in their application to any particular make or style of press but are of broad application to bed and platen presses in general.

With these ends in view our improvements comprise features illustrated in the drawings accompanying this specification, wherein:

Figure 1 is a side elevation of so much of a printing press of the character described as will suffice to illustrate our improvements. Figure 2 is a plan view corresponding with what is shown in Figure 1. Figure 3 is a fragmentary sectional elevation on line 3—3 of Figure 1. The scale of all the figures is the same.

Our improvements are illustrated as applied to a two-station or double color press, wherein two forms 2, 40 are mounted by known means side by side on form carrier 4. The carriage 5 is mounted for transverse reciprocation on platen 6 and is retained thereon by gibbs 7, 7. Said platen is oscillated on shaft 8 and is actuated from known means, not shown, through link 9. Stops 10, 11 are provided near opposite edges of platen 6 to limit the movement of carriage 5. Wheel 12, fixed to shaft 13 makes one rotation for each cycle of movement of platen 6 to and from form carrier 4, by known means, not shown. Pivotedly mounted on the lower edge

of carriage 5 are the usual grippers 14, 14 for holding a sheet, as 15, against the face of said carriage. Said grippers are fixed to shaft 16 and may be spring urged to engagement with sheet 15. For lifting said grippers there is provided at one side of the machine fixed cam 17 extending upwardly from side frame 180. Fixed to shaft 16 is down-reaching arm 19 having pin 20 extending therefrom for engagement with said cam 17.

For causing carriage 5 to reciprocate transversely on platen 6 the following means are provided: Projecting rearwardly and downwardly from the upper end of carriage 5 is cam 21, arranged substantially concentric with shaft 8. Said cam has opposite operative faces 21^a, 21^b, meeting at their lower ends 21^c in a wedge like point.

For engagement with said cam alternately on faces 21^a, 21^b, is cam roll 22 rotatively mounted on pin 23 fixed in the forwardly projecting end of arm 24. Said arm is fixed to slide 25, mounted for transverse movement in gibbed ways 26, 27 of cross bar 28 fixed to side frames 18, 180. For causing said slide 25 to reciprocate transversely of the machine, crank 29, pivoted on stud 30, fixed in crossbar 28 and near that end thereof contiguous to wheel 12, is provided. Said crank 29 is provided with crankpin 31 which is connected with pin 32 of slide 25 by link 33. The hole in one end of link 33, as at 34 about pin 32, is elongated to provide a slight movement of slide 25 independent of the movement imparted thereto by crank 29, for purposes which will appear later herein.

Embodied with crank 29 is starwheel 35 having an even number of teeth, as four. Said starwheel is located in tangential relation to wheel 12, Fig. 1, and in position to have its teeth engaged by peripheral pins 36, 37, respectively, of said wheel, as said wheel rotates in clockwise direction, Fig. 1.

The operation of our improved machine is as follows: The parts being in the relative positions of Figs. 1 and 2, with carriage 5 against stop pin 10 of platen 6, a sheet 15, to be printed, is placed on the face of said carriage, where it may be located by the usual gage pins if desired. The press now being started, platen 6 swings toward form carrier 4 and grippers 14 are released by cam 17 and close down onto the edges of sheet 15, thereby holding said sheet securely on carriage 5. It will be understood that

the press is equipped with suitable means for inking forms 2, 40, of known character, not shown. Such inking will have been accomplished at this time and the inking means will have retired to permit contact between the sheet on carriage 5 and form 2 opposite thereto on form carrier 4. As platen 6 swings in anticlockwise direction to present carriage 5 against form 2, cam 21 is carried forwardly away from roll 22 far enough for the point of said cam (see dotted position Fig. 2) to clear said roll as that roll is moved transversely to its dotted position in said Fig. 2. During the forward movement of platen 6 toward form carrier 4, pins 36, 37 on wheel 12 are moved into successive engagement with successive teeth of starwheel 35 thereby imparting to that wheel and to crank 29, a half revolution. This half revolution, through link 33, moves slide 25 and cam roll 22 toward frame 180 of the machine. The new location of said cam roll is shown in dotted lines in Fig. 2, and when said roll is thus positioned, pin 32 is against that end of elongated hole 34 nearest pin 31, which allows pin 32, slide 25 and cam roll 22 to be moved a slight distance farther toward side frame 180 as hereinafter referred to. Sheet 15 on carriage 5 having made its contact with form 2 and received its impression therefrom, platen 6 now commences to swing back away from form carrier 4 and directly thereafter face 21^b of cam 21 engages roll 22 (dotted position Fig. 2) whereby roll 22 is forced slightly toward frame 180 until slide 25 strikes abutment 38 and pin 32 moves to the middle of elongated hole 34 in link 33. By this arrangement link 33 and crank 29 are relieved of all strain of operating cam 21, that strain being taken by abutment 38. Upon the further swinging back of platen 6, carriage 5 is forced transversely toward side frame 18. The transverse movement of carriage 5 progresses sufficiently to carry pin 20 out of engaging relation with cam 17 before said pin encounters the operative portion of said cam, whereby grippers 14, 14 continue to maintain their gripping action of sheet 15 against carriage 5. As platen 6 continues to swing backwardly, roll 22 is engaged by the higher portion of cam face 21^b, thereby moving carriage 5 finally against stop 11 near frame 18, whereby the first impression on sheet 15 on said carriage is brought into position to register with the second form, 40. During the next rotation of wheel 12, platen 6 swings up to meet form carrier 4, and pins 36, 37 engage starwheel 35, thereby rotating that wheel a half revolution. This causes crank 29 to move slide 25 toward frame 18 close to abutment 39, that end of elongated hole 34 in link 33 nearest frame 180 engaging pin 32 of slide 25, whereby roll

22 is positioned for engagement with face 21^a of cam 21 as platen 6 swings backwardly toward the position shown in full lines in Fig. 2. Platen 6 then swings backwardly and face 21^a of cam 21 engages roll 22 and forces slide 25 against abutment 39 and pin 32 to the middle of elongated hole 34 in link 33 thereby relieving the strain on link 33 and crank 29. Carriage 5 is thus caused to reciprocate toward frame 180 until it encounters stop 10. As carriage 5 moves toward frame 180, pin 20 again passes under cam 17, and as platen 6 swings backwardly to the position of Fig. 1, said pin engages said cam and grippers 14 are lifted from sheet 15. Said sheet, now having received two impressions in register and having been returned to its first position may be removed and a new sheet substituted for a repetition of the operation.

It will be understood that, while we may omit the lost motion connection between the end of link 33 and pin 32, by careful and accurate adjustment of the relation between cam 21 and roll 22, nevertheless the mechanism works with less pounding and with greater accuracy of register by employing said lost motion connection and by throwing the strain against abutments 38, 39, relieves link 33, crank 29 and starwheel 35 of all strain incident to the shifting of carriage 5.

We claim:

1. In a printing press of the character described the combination of a platen, a carriage mounted for transverse movement on said platen, a form carrier adapted for supporting two forms adjacently arranged transversely of the press, a two faced cam fixed to said carriage, a roll adapted for alternate engagement with said cam faces, and means operable during each cycle of movement of said press for shifting said roll from engaging relation with one of said cam faces to engaging relation with the other of said cam faces.

2. In a printing press of the character described the combination of a platen, a carriage mounted for transverse movement on said platen, a form carrier adapted for supporting two forms adjacently arranged transversely of the press, a two faced cam fixed to said carriage, a slide mounted for movement transversely of said platen, a roll carried by said slide, and means operable during each cycle of movement of said press for causing said slide to shift said roll from engaging relation with one of said cam faces into engaging relation with the other of said cam faces.

3. In a printing press of the character described the combination of a platen, a carriage mounted for transverse movement on said platen, a form carrier adapted for supporting two forms adjacently arranged transversely of the press, a two faced cam

- fixed to said carriage, a slide mounted for movement transversely of said platen, a roll carried by said slide, means for causing said slide to shift said roll from engaging relation with one of said cam faces into engaging relation with the other of said cam faces comprising a wheel which makes one rotation for each cycle of movement of said press, a crank and a starwheel operably connected, means on said wheel for engagement with said starwheel adapted for rotating said starwheel one-half revolution for each rotation of said wheel, and a link connecting said slide and said crank.
4. In a printing press of the character described the combination of a platen, a carriage mounted for transverse movement on said platen, a form carrier adapted for supporting two forms adjacently arranged transversely of the press, a two faced cam fixed to said carriage, a slide mounted for movement transversely of said platen, a roll carried by said slide, means for causing said slide to shift said roll from engaging relation with one of said cam faces into engaging relation with the other of said cam faces comprising a wheel which makes one rotation for each cycle of movement of said press, a crank and a starwheel operably connected, means on said wheel for engagement with said starwheel adapted for rotating said starwheel one-half revolution for each rotation of said wheel, and a link connecting said slide and said crank, said link having a lost motion connection at one end thereof.
5. In a printing press of the character described the combination of a platen, a carriage mounted for transverse movement on said platen, a form carrier adapted for supporting two forms adjacently arranged transversely of the press, a slide mounted for movement transversely of said platen, a two faced cam and a roll for alternate engagement with said cam faces interposed between said slide and said carriage, means governed by said slide for shifting the re-
- lation of said cam and roll, said cam and roll being adapted for shifting said carriage alternately in opposite directions transversely of said platen, and means operable during each cycle of movement of said press for shifting said slide transversely of said platen.
6. In a printing press of the character described the combination of a platen, a carriage mounted for transverse movement on said platen, a form carrier adapted for supporting two forms adjacently arranged transversely of the press, means operable during each cycle of movement of said press for shifting said carriage transversely of said platen, a spring actuated gripper pivotally mounted on said carriage, and means operable when said carriage is in one position on said platen for lifting said gripper, said means being inoperable when said carriage is in a position on said platen remote from said first mentioned position.
7. In a printing press of the character described the combination of a platen, a carriage mounted for transverse movement on said platen, a form carrier adapted for supporting two forms adjacently arranged transversely of the press, means operable during each cycle of movement of said press for shifting said carriage transversely of said platen, a spring actuated gripper pivotally mounted on said carriage, a fixed cam adjacent one side of the press, and an arm carried by said gripper for engagement with said cam, said arm and cam being adapted for lifting said gripper when said arm and cam are in engaging relation, said arm being in engaging relation with said cam when said carriage is at one end of its travel and out of engaging relation when said carriage is at the other end of its travel.

In witness whereof, we hereby affix our signatures this 19 day of March, 1923.

LESLIE M. PAGE.
LOUIS MEYLACH.
